UNITED STATES PATENT OFFICE

ELMER C. NORTHRUP, OF SAN FRANCISCO, CALIFORNIA

BOX MACHINE

Application filed September 3, 1929. Serial No. 390,015.

This invention relates to automatic box making machines of the type shown in my issued Patents Numbers 1,058,894 and 1,144,497, and the objects of the invention are to provide improvements in the general construction of such a machine whereby its efficiency will be increased and whereby it may be adjusted for various sizes and kinds of boxes.

- 10 In the drawings hereto Fig. 1 is a perspective view of the complete machine as seen from the front and with a three-headed box partially completed shown in position on the table.
- 15 Fig. 2 is a perspective view of the machine from the rear side showing the four stacks of boards or rather three stacks of heads and one stack of side and bottom shooks in place in their hoppers.

- 20 Fig. 3 is a side elevation of the machine in section showing the relation of its principal elements.

- Fig. 4 is an enlarged front view of the lower portion of the machine showing the table actuating cam mechanism.

- Fig. 5 is a plan view of Fig. 4.

- Fig. 6 is an enlarged vertical section showing the operation of the reciprocating shook and head feeding mechanism with carriage retracted.

- Fig. 7 is a view similar to that of Fig. 6 but with carriage advanced and shook feeding arms dropped to clear the delivered shooks for return stroke.

- 35 Fig. 8 is an enlarged detail of one of the hooks which engage the edges of the shooks.

- Fig. 9 is an enlarged front view of one of the revolvable triangular shook feeding arms upon which the hooks of Fig. 8 are mounted.

- 40 Fig. 10 is a cross section of the rear end of the device of Fig. 9 showing the pin chuck for periodically revolving the shook feeding bar.

- 45 Fig. 11 is a broken sectional side view of Fig. 10.

- Fig. 12 is an enlarged vertical section of the vertically slideable cross head showing one series of nailing chucks and associated parts.

- 50 Fig. 13 is a broken front view of Fig. 12

partly in section showing the internal construction of the members.

Fig. 14 is a sectional detail of the center chuck bracket connection to its supporting cross head.

Before entering a detailed description of my improvements attention is drawn to the complete description of similar machines in my two prior patents mentioned so that repetition will not be necessary in describing in detail hundreds of parts which tho slightly changed in form are the equivalent of what was shown and described before, and the present description will be directed insofar as is practicable to those features which are distinctly new and sought to be covered in the appended claims.

Briefly described, the machine is of the type wherein stacks of box heads and box sides or "shooks" are placed in hoppers at the rear to be automatically picked off and assembled on a nailing table with one side of the box in place on the heads, the side nailed, box turned to another side, another side board or shook positioned, nailed, same operation repeated on the third side, and the next movement ejecting the completed box (three sides nailed and one side left open) by the oncoming new heads and positioning the new heads and one side in place on nailing table for next box. Nails are fed automatically from a rocking type of nail feeding mechanism and picked off in the right quantities for the different sides to be nailed by mechanism indicated in the drawings of a general type well understood in the art and not claimed in the present application.

Such automatic machines heretofore have never been capable of producing three-headed boxes such as lemon boxes having an extra central head, nor have they been adjustable for different sizes or types of boxes, whereas the present machine will make two or three headed boxes and various size boxes by slight change in some detachable and movable parts, and also shallow boxes of relatively great width such as fig and berry boxes. Other advantages of the machine will appear in the description and drawings.

With reference to the drawings the machine comprises a base 1, frame elements 2, clutch controlled power application shaft 3 geared to a main cam shaft 4 which controls 5 and times all of the movements of the machine.

At the top of the machine is the automatic nail feeding and selecting apparatus 5 not detailed as not involved herein, while at the 10 back of the machine at opposite sides thereof are two stacks of box heads 6 in slanted hoppers 7, one stack of center heads 8 in slanted hopper 9, and a central stack 10 of horizontally disposed thin boards or box "shooks" 15 to form the sides and bottoms of the boxes, the shooks being prearranged in wide and narrow widths in the sequence of their use as well understood and as indicated in Figs. 6 and 7. It should be noted that all four 20 stacks of material may be replenished by one operative from the rear of the machine. Rolling weights 122 against the outer heads in the stacks are provided to gently urge the heads inward.

25 A horizontally reciprocating carriage 11 moved back and forth on the frame by a Y-shaped pivotally connected arm 12 operated by a rod 13 from suitable cam 14 on the cam shaft feeds the heads and shooks from the 30 stacks forwardly and positions them over a nailing table 15 with heads aligned under nailing chucks 16, and with each head clamped against opposite sides by rotatable disks 17 and which disks are revolved a quarter turn 35 as each side is nailed in place to the heads, through means of a slotted locking star wheel 18 operated by a pin (not shown) on cam shaft drive gear 19, star wheel 18 being mounted on a shaft 20 and suitably geared or 40 chain driven as at 21 to periodically turn the head clamping disks 17.

Clamping disks 17 are mounted on short aligned shafts substantially as in the prior disclosures, the outer ones supported in the 45 main frame of the machine and the inner ones in bearings 22. The outer disks are periodically forced inward to clamp the outer heads by wedges formed on the upper ends of rods 23 actuated at the proper time by cams 50 24 and the inner disks are simultaneously and resiliently spread apart by wedges 25 on the upper forked ends of a rod 26 engaging between sleeves 27 and springs 28 on the inner disk shafts. The wedge rod 26 being periodically raised and lowered from a suitable cam connection 29 to the main cam shaft.

During the turning of the box the nailing 60 chucks and punches are lifted, and the nailing table is lowered to provide the necessary clearance for the box to turn, the chucks being carried on a cross head 30 and the punches on a nailing cross head 31 vertically slidable on the frame 2 and simultaneously though independently raised and lowered respectively 65 by rods 32 and 33 operated from the main cam

shaft 4 as indicated, while the table 15 is raised and lowered by means of two large cams 34 on main cam shaft rolling against rollers 35 carried by table bed frame 36.

Table bed frame 36 comprises two end pieces 36 connected by bars 36' and is vertically guided by means of two vertical guide bars 37 secured to its opposite ends and slidable in bearings 38 on the frame, while mounted upon the end pieces and slidable transversely of the machine (longitudinally of the box to be made) are table chucks 39 provided with three different heights of steps 40, 41, 42 for supporting the nailing table at the three different heights necessary in successively 80 nailing the sides and bottom on the box heads. Steps 41 and 42 are detachable as by screws or other suitable means so that other steps of any desired size may be substituted as may be required for the particular dimension of boxes 85 being run, and in operation of the machine the different steps come automatically into position beneath the supporting surfaces 43 by the sliding of the table chucks 39 in and out to the proper point as the box is being turned 90 when the table is lowered.

The table is a large inverted channel and is guided vertically on guides 44 at its corners. It does not descend the full distance of the chucks 39 but is arrested by spring stops 45 95 so that the chucks are free for operation beneath it and pick it up again upon the next upward movement.

The chucks are slid back and forth to the proper place to bring the required chuck steps 100 under the table by means of a revolving double face cam 46 formed upon a gear body 47 suitably geared from the main cam shaft by a pinion 48. The sides or faces of the cam operating against roller cam levers 49 pivoted to the framing at one end and carrying rollers 50 at their other ends bearing against spreader arms 51 carried at the inner ends of bolt rods 52, and which spreader arms are forced apart by rollers 50 upon revolution of the cam 46 110 and forced together as the cam surfaces fall away by means of a compression spring 53 on a rod 54 secured to the right-hand arm 51 (Fig. 4) and extending loosely through the left-hand arm 51, the spring reacting between 115 a nut on the end of the rod and the left-hand arm.

The table chucks may be used as the nailing support for two headed boxes without the table 15, and the chucks may be independently 120 adjusted by means of bolts 52 for any length of box within the capacity of the machine, this feature combined with the replaceable steps 42 provides for boxes of all dimensions in so far as the nailing support is concerned. The 125 several heights of the steps it should be noted are to compensate for the unequal breadth and height of the boxes as well as to allow for the additional thickness of the first applied side shook which lies upon the table when 130

nailing the last side in place, the object being that the extreme upper surface of the box being nailed will always be in the same horizontal plane when the table 15 is elevated 5 under it regardless of the unequal dimensions of the box, and with a fixed rise and fall of the table bed frame 36 by revolution of main cams 34.

Cams 34 keep revolving during the driving 10 of the nails and are provided with hardened inserted sections 34' which are in place under rollers 35 during the nailing operation. These sections 34' are removable so that they can easily be replaced when worn.

15 The nailing chucks 16 are arranged in three rows, each aligned with one of the box heads as shown in Fig. 1 and each row carried on nailing chuck brackets 55 along which each chuck is independently slideable through the 20 provision of a T slot 56 engaging chuck bolt 57 tightened by nut 58.

The three chuck brackets are carried on the cross head 30, the two outer ones adjustable horizontally on the cross head, and the inner 25 one arranged to have limited vertical movement thereon of about half an inch so that the center chucks can accommodate themselves to a higher or lower box head. This construction is shown in Fig. 14 wherein the 30 slotted engagement of chuck bracket 55 with cross head 30 is indicated at 59. The adjustability of the end chuck brackets on cross head 30 is indicated in Figs. 12 and 13 at 124.

Extending through the upper end of each 35 nailing chuck 16 is a nail punch 60 secured at its upper end to a block 61 separately adjustable along a nailing head bracket 62 and clamped thereagainst by plate 63 and bolts 64, and the nailing head brackets are individually mounted for limited vertical sliding 40 movement along the surface 65 on a nailing head 66 carried by the nailing cross head 31 as shown in Fig. 13 and wherein the nailing head bracket is shown forced down to a stop 45 67 on the nailing head by means of a very heavy coil spring 68 carried within the nailing head and reacting against the nailing head bracket 62 and an adjusting screw 69 projecting from the upper side of the nailing head. The two outer nailing heads are adjustable horizontally along the cross head 31 and clamped by bolts 125.

50 Coil spring 68 is of sufficient power to force all nails of one row of chucks into the box upon descent of the cross arms 30 and 31 and yet permit the nail punches 60 to back up slightly without material injury to the wood. Screw 69 serves for adjusting the power of the spring to suit the size nail or 55 grade of wood being operated on.

Cross heads 30 and 31 as stated move part 60 of their travel simultaneously but not for the full distance, as chucks 16 stop firmly against the shook to be nailed, while cross head 31 65 carries on down to force the nail punches

down, the nails being fed to the chucks below the punches by the usual feed pipes 70 carrying cups 71 at their upper ends all positioned in a single row across the machine, with the cups for each set of chucks carried as a group 70 on separate bars 72, 72', 72'' each respectively supported at the upper end of a vertical rod 73 secured at its lower end to the nailing chuck bracket 55 and guided loosely through the nailing head 66 as shown in Fig. 13 so 75 that upon rising of the nailing cross heads 30 and 31 to permit box to turn the nail cups 71 will be elevated to receive their nails from the nail feeding apparatus 5.

Returning to Figs. 2, 3 and 6 to 11, in feeding the heads and shooks forwardly by the reciprocating movements of carriage 11, lugs or fingers 74, 87 on the carriage and which push against the rear edges of the lowermost boards of the hopper to force them to position between clamping and turning disks 17, do not come back far enough to allow the heads to fall in front of them for the reason that it is only desired to feed the heads at every third forward stroke as the two intermediate strokes carry shooks only and therefore levers 75 are provided to impinge the rear edge of the inner boards of each outer stack and for the central heads so as to force the heads far enough forward to fall in front 95 of the fingers.

These levers 75 are moved forwardly every third stroke of the carriage by means of a cam 76 on a shaft 77 constantly revolved by suitable chain gearing 78 from the main cam 100 shaft 4, the center head being lifted by an elevating arm 79 pivoted at one end at 80 to the frame and periodically lifted by suitable cam connections to the main cam shaft so that its other end provided with a suitable clip 81 105 will engage under the lowermost center head of the stack and lift it along a suitable guide 123 for forward ejection by the carriage with the two outer heads as described.

In Fig. 3 the lower hopper 9 is shown 110 empty and arranged on the slanted bottom is seen an endless feed chain 82 against which the lower edges of the boards rest, and which chain passes over a small idler at its upper end returns under the hopper and over a 115 small sprocket (not seen) at the lower end secured to a shaft 83 having a ratchet wheel 84 at its outer end tripped by a pawl 85 secured to the pivot shaft 86 of carriage operating arm 12, so that the chain will gently 120 urge the heads 8 downwardly as the machine is operated, the chain traveling a trifle faster than necessary.

The shooks from stack 10 are fed from beneath the pile by means of two triangular 125 arms 86 which project forwardly from the carriage 11. These arms in cross section show three substantially radial ribs each of which is fitted with a plurality of hooks 87 adapted to grip the edges of the lowermost 130

shook and carry it forward to nailing position upon forward movement of the carriage.

Hooks 87 are variously positioned along the three ribs of the arm 86 so as to suit the width and number of shooks to be carried forward for the bottom or side of a box and the arm makes a third revolution on each return stroke so as to present the next set of hooks in place for carrying the shooks for the next side formed. Fig. 6 shows one hook about to take a wide shook and another hook following for the next wide shook, both of which will be carried forward to the bottom of the box now turned upward on the table to receive them.

The hooks are pivotally mounted on the arms at 88, resiliently forced upward by a small spring 89 to a point which may be determined by a screw stop 90, and of course they may be in any number and position along the bar.

As each set of shooks is carried forward on the arms 86 they pass above the upper edges of the box ends and below arched springs 91 which are attached to and extend below two holding down weights 92 pivotally hung on rods 93 projecting from frame of machine, so that the shooks will be held down firmly along two lines lying between the heads of a two or three-headed box during the nailing operation yet allow for any variations in material.

Shook feeding arms 86 are pivotally mounted for horizontal rotation in members 94 in turn horizontally pivoted at 95 to the carriage so that the member 94 and rotatable arm can be lowered at the end of the forward stroke to return clear of the delivered shooks. The arms are normally held up in horizontal position by pivoted latches 96 actuated by springs 97 and which latches are kicked out by striking adjustable stop screws 98 on the fixed frame of the machine as shown in Fig. 7.

When latch 96 is kicked out a pivoted lever 99 carried by member 94 falls as shown in Fig. 7 and pulls down a link 100 which has a tooth 101 on its forward side (see Figs. 10 and 11) and functions as a pawl against pins 102 projecting from rear hub 103 of shank 104 of shook feeding arm 86 so as to revolve the arm 86 one-third of a revolution every time lever 99 is raised.

Upon return stroke of carriage the lower slanted face of lever 99 rides over an idler 105 carried on shaft 77 and rises as position shown in Fig. 6 whereupon latch 96 springs into position holding the parts in place for the next advance movement of the carriage.

Also provided is an intermittent support for rearwardly projecting wide shooks of stack 10 so that if warped or if in two pieces they will not fall or be prematurely picked off by shook feeding arms. This device comprises a slidably flat rod 106 at each side of the machine arranged so that the forward

ends of the rods will project under the overhanging wide shooks as shown in Fig. 7. The rear ends of the rods are pivoted at 107 to vertical levers 108 pivoted at their lower ends at 109 to the frame and which levers are normally pulled forward by springs 110 and pushed back at the proper intervals by means of cams 111 secured to shaft 77 which revolves at the proper speed to pull the supporting rods 106 from under the overhanging shooks when the wide shooks are being fed forwardly by the feeder arms 86.

In the making of wide shallow boxes such as fig boxes, it is necessary to make the feeder carriage travel a lesser distance when feeding the shook to the last narrow side of the box so that the arms 86 do not force out the bottom of the box previously nailed in place. The length of stroke for placing the first side does not matter as there is then no bottom to interfere, hence when working on such boxes the carriage should have two long strokes followed by a short stroke for each box, and to take care of this the cam actuated rod 18 which oscillates the carriage reciprocating arm 12 is not directly pivoted to the arm, but is instead pivoted at 112 to a bell crank lever 113 itself pivoted at 114 to the arm, and the free end of the crank carries a roller 115 bearing on the rim of a disk 116 revolved in time with the other machine elements by suitable gearing such as the chain 117 taking its motion from the main cam shaft.

Disk 116 is secured to the driving sprocket 118 to run free on shaft 126 and is cut away at 119 so that roller 115 can fall during a portion of its revolution corresponding to the time period at which the short stroke is required. When the roller falls into the gap 119 no movement of the arm 12 can take place until the crank 113 strikes an adjustable stop screw 120 carried on the arm and by which the stroke of the arm is determined. As the full portion of the rim comes around the roller is lifted from the gap and the long stroke is resumed, the full rim being twice the arc of the gap gives two long strokes to one short stroke of the carriage.

A pin 121 is provided which may be inserted in coinciding holes in crank and arm to prevent change of stroke when operating on substantially square boxes.

When making very shallow boxes the large rotating disks 17 shown in the drawings may be removed and smaller ones or any other form of clamping plates substituted which the shape of the box may necessitate to avoid interference with bottom shooks.

Having preceded the description with a schedule showing the sequence of operations, the additional explanation of the action of each improved feature above given is thought to make the operation of the machine perfectly clear to anyone having a general

knowledge of such mechanisms and while every cam and bolt on the machine has not been specifically numbered and described, this would but unnecessarily lengthen the specification while adding nothing of value to the record.

I claim:

1. In a box making machine, a nailing table above which the box is assembled, means for assembling the box elements including two heads above and clear of said table for nailing, means for simultaneously assembling a third head above and clear of said table at an intermediate point between said two heads, and means for raising the table to contact the heads.

2. In a box making machine, a nailing table above which the box is assembled, means for assembling the box elements including two heads above said table for nailing, means for simultaneously assembling a third head above said table at an intermediate point between said two heads, said last mentioned means including an elevator lifting the third head from a supply at the lower part of the machine, and means for ejecting the third head laterally from the elevator over the table.

3. In an automatic box making machine adapted to assemble the box elements and nail the same, an assembling support, three separate stacks of box heads and a stack of shooks carried by the machine, and means for simultaneously carrying a head from each stack in spaced relation to said assembling support and the shook for one side in position for nailing to the three heads, one of the stacks of heads being positioned below the other stacks, and elevating means provided for periodically raising a head from the lower stack to alignment with heads of the other stacks preparatory to carrying the three heads to said assembling support.

4. In an automatic box making machine adapted to assemble the box elements and nail the same, an assembling support, separate stacks of box heads and shooks carried by the machine, reciprocating means for carrying the heads and shooks to said support in assembled position for nailing, said means operating in succession first on heads and shooks for one side of box, second on shook for bottom of box and third on shook for other side of box, and means positively operated whereby the stroke of said reciprocating means will be shorter when operating on the bottom shooks so as to adapt the machine for relatively wide shallow boxes.

5. In a structure as specified in claim 4, means for predetermining the length of the short stroke to suit the box being made.

6. In an automatic box making machine adapted to assemble the box elements and nail the same, an assembling support, means for delivering spaced box ends in vertical

position to said support with a shook thereon in position for nailing, and a weight under which said shook is slid to position, said weight supported with freedom to rise and fall above the shook and a spring carried by 70 and projecting below said weight for bearing down first upon the shook.

7. In an automatic box making machine adapted to assemble the box elements and nail the same, an assembling support, means for delivering spaced box ends in vertical position to said support with a shook thereon in position for nailing, yielding hold-down means under which said shook is slid to position, said yielding hold-down means including a weight supported with freedom to 75 rise and fall above the shook for bearing down on the same, and a spring on the lower side of said weight pressing against the shook.

8. In an automatic box making machine, a reciprocating shook feeder adapted to pick a shook from beneath a pile and carry it to box assembling position, said feeder including an arm provided with three substantially radial ribs, and shook engaging hooks on said ribs.

9. In an automatic box making machine, a reciprocating shook feeder adapted to pick a shook from beneath a pile and carry it to 95 box assembling position, said feeder including an arm provided with three substantially radial ribs, shook engaging hooks pivotally mounted on said ribs, resilient means for forcing said hooks to gripping position outward of said ribs, and means for adjusting the extent of the projection of said hooks.

10. In an automatic box making machine, a reciprocating shook feeder adapted to pick a shook from beneath a pile and carry it to 105 box assembling position, said feeder including an arm provided with three substantially radial ribs, shook engaging hooks on said ribs, and means for revolving said arm a third revolution between each shook feeding stroke of the arm so as to bring another of said ribs to position under the shook to be fed.

11. In an automatic box making machine, a reciprocating shook feeder adapted to pick a shook from beneath a pile and carry it to 115 box assembling position, said feeder including an arm provided with hooks at various points thereon for engaging the edge of a shook, a holder at one end of said arm in which said arm is revolvably mounted, means pivoting said holder at one end for bodily rising and falling of said arm and holder, a latch normally holding said arm elevated in horizontal extension, and means at the shook delivery end of the stroke for kicking out said latch whereby said holder and arm can fall for the return stroke.

12. In a construction specified in claim 11, a lever pivoted at one end to said holder to fall below the same, a link pivoted to the free 130

end of said lever provided with means adapted to engage said arm and revolve the same upon lifting of said lever, and means for lifting said lever upon the return stroke of said arm.

13. In a box making machine, supporting means upon which the box is assembled comprising a table arranged for vertical movement, cam means below the table arranged for raising and lowering the table the same distance each movement, and a plurality of different height steps consecutively interposed between the table and cam means adapted for varying the working height to which said table is raised.

14. In a box making machine, supporting means upon which the box is assembled comprising a table arranged for vertical movement, cam means below the table arranged for raising and lowering the table the same distance each movement, a plurality of different height steps consecutively interposed between the table and cam means adapted for varying the working height to which said table is raised, and means for moving said steps to bring any of them into required position.

15. In a box making machine, supporting means upon which the box is assembled comprising a table arranged for vertical movement, cam means below the table for raising and lowering the same, a plurality of different height steps interposed between the table and cam means adapted for varying the working height to which said table is raised, means for moving said steps to bring any of them into required position comprising spaced chucks at opposite ends of the table upon which the steps are mounted, said chucks supported by said cam means, and means for guiding the chucks toward and from one another for bringing the required steps into place.

16. In a box making machine, supporting means upon which the box is assembled comprising a table arranged for vertical movement, cam means below the table for raising and lowering the same, and a plurality of different height steps interposed between the table and cam means adapted for varying the working height to which said table is raised, said steps being detachably secured in place whereby they may be interchanged with other size steps as required for various size boxes to be made.

17. In a box making machine, a cam shaft, a pair of spaced rim cams thereon, a member above each rim cam guided for vertical movement and provided with a roller against which the rim cam revolves, a pair of chucks provided with step supports on top, each chuck slidably supported on one of said members in a direction toward and from one another, and means timed with said cam shaft

for periodically sliding said chucks back and forth.

18. In a box making machine, a cam shaft, a pair of spaced rim cams thereon, a member above each rim cam guided for vertical movement and provided with a roller against which the rim cam revolves, a pair of chucks provided with step supports on top, each chuck slidably supported on one of said members in a direction toward and from one another, a second cam operating in time with said cam shaft, and means operated by said second cam for periodically sliding said chucks back and forth.

19. In a box making machine, a pair of box supporting chucks, various height steps upon the chucks, means whereby said chucks are slidably guided for horizontal movement, means for sliding the chucks toward and from one another in direction transversely of said steps, a box supporting table supported above said steps, and means for raising and lowering said chucks to successively bring said various height steps in contact with and for raising and lowering said table.

20. In a box making machine, a pair of box supporting chucks, various height steps upon the chucks, means whereby said chucks are slidably guided for horizontal movement, and means for sliding the chucks toward and from one another in direction transversely of said steps, said steps being detachably mounted on the chucks whereby they may be removed for replacement with steps of other size, a box supporting table supported above said steps, and means for raising and lowering said chucks to successively bring said various height steps in contact with and for raising and lowering said table.

21. In a box making machine, means for supporting a box for nailing, three spaced rows of nail chucks arranged to descend against the box, means for vertically moving the chucks, and means whereby the central row of chucks may lag with respect to the two outer rows when descending against the box.

22. In a box making machine, means for supporting a box for nailing, a nail chuck cross head vertically slidable above said box, a plurality of brackets carried by said cross head, a row of nail chucks on each bracket individually adjustable therealong, a nailing head bracket vertically slidable above each row of chucks, a member vertically slidable on each nailing head bracket above each row of chucks, nail punches extending from said member to each chuck, and a compression spring positioned between each said member and its nailing head bracket.

23. In a box making machine, means for supporting a box for nailing, a nail chuck cross head vertically slidable above said box, a plurality of brackets carried by said cross head, a row of nail chucks on each bracket individually adjustable therealong, a nailing

head bracket vertically slideable above each row of chucks, a member vertically slideable on each nailing head bracket above each row of chucks, means for limiting the movement of said member on its nailing head bracket, nail punches extending from said member to each chuck, a compression spring positioned between each said member and its nailing head bracket, and means for separately varying the effective pressure of each compression spring.

24. In a construction as specified in claim 22, power transmitting means positioned below the box support for periodically raising and lowering said nail chucks and nailing head brackets to bring said chucks against the box and to compress the springs.
